MULTIPLE COMPARTMENT PACKAGE

Stephen A. Van Mil, Jr., Union, N.J., assignor to Ivers-Lee Company, Newark, N.J., a corporation of Delaware

Filed Apr. 18, 1962, Ser. No. 69,766

Term of patent 14 years

(Cl. D58—2)

I claim:

The ornamental design for a multiple compartment package as shown and described.
